VENDING MACHINE WITH HYDRAULIC
ACTUATING MECHANISM
Goffredo Tremolada, Via Consale Marcello 10,
Milan, Italy
Filed Oct. 3, 1960, Ser. No. 60,058
12 Claims. (Cl. 194—10)

This invention relates to an automatic vending machine for articles of different type which is operated by the introduction of a coin or a token and is provided with a selecting device to allow, by the operation of a corresponding pushbutton or handle, the dispensing of the desired article.

More particularly the invention relates to a vending machine having a central hydraulic control system adapted to operate the various dispensing devices independently upon the actuation of the corresponding selector members.

Conventional vending machines, used for the distribution of identical or diversified articles, have discharging devices which are operated by means of mechanical transmission elements such as gears and chains. These known machines are particularly liable to failures (such as "binding" and "seizing") of the various dispensing elements as the mechanism becomes worn in prolonged use.

These disadvantages are entirely eliminated in an automatic vending machine which, in accordance with the present invention, comprises a hydraulic dispensing control. The latter advantageously includes a hydraulic distributor to which a fluid (generally oil) under pressure is fed from a reservoir in a closed cycle which includes a plurality of pairs of conduits for reversibly admitting the fluid to respective hydraulic cylinders under the control of valve means responsive to the several selector members.

The valve means may advantageously consist of a solenoid-actuated slide valve for each of the storage compartments or magazines of the vending machine. The pistons effect a reciprocating rectilinear movement of respective sliders, located at the bottom of each magazine, whose displacement successively dispenses the articles contained in the compartments.

According to a further feature of the present invention, the central distributor feeds the cylinders with oil or other fluid under pressure in such a way that only one cylinder at a time may be actuated to shift the piston and, therefore, the corresponding slider while the remaining pistons of the other cylinders are held inactive. The operated cylinder may correspond to a particular selector member actuated after the introduction of the coin or token, or several cylinders may form a group controlled by one selector for successive operation as the corresponding compartments become exhausted.

The invention also contemplates the utilization of a single driving element connected to one end only of a respective slider, the latter being advantageously guided in its reciprocating movement by a sliding sleeve adapted to insure proper alignment.

According to yet another feature of the present invention the framing members which constitute the various compartments or magazines are adjustable in two mutually perpendicular directions in order to accommodate articles of different sizes.

Additional objects, features and advantages of the present invention will become more readily apparent from the following detailed description, reference being made to the accompanying drawing in which:

FIG. 1 is a perspective view of a vending machine according to the invention with the front cover thereof removed;

2

FIG. 2 is a cross-sectional view of a portion of the machine, partly diagrammatic and drawn to a larger scale;

FIG. 3 is an axial cross-sectional view of the hydraulic distributor of the machine;

FIG. 4 is a cross-sectional view of the distributor taken along line IV—IV of FIG. 3;

FIG. 5 is a cross-sectional view of the distributor taken along line V—V of FIG. 3;

FIG. 6 is a diagram of a hydraulic circuit for the machine showing only one piston; and

FIG. 7 is a circuit diagram of the electric control system for the machine illustrated in FIGS. 1—6.

The automatic vending machine about to be described is particularly suitable for the distribution of different beverages contained in cylindrical bottles B², B³, B⁴, B⁵ and B⁶.

The machine comprises a closed body 1 the upper section of which is divided into various compartments 2, 3, 4, 5 and 6 by vertical guides 7, 7' (FIG. 2) carried upon rails 107. The width of the compartments 2 to 6 can be increased or reduced by adjusting the horizontally shiftable rails 107 on the suitably slotted supporting beams 11, 11' while the depth of the compartments may be varied by displacing the guides 7, 7' along the rails 107. Each compartment contains bottles of one particular kind of drink. In the lower section of the body 1 are mounted a pump 36' driven by a motor 136, a central distributor 8 (not visible in FIG. 1), a fluid reservoir 35 and the radiator assembly of a cooling unit 90 whose other parts are located in an intermediate section of body 1 along with a chute 9 for conveying the bottles B² to B⁶ from the various compartments towards a common outlet opening at the front of the machine.

As can be seen from the drawing, the width of each vertical compartment 2 to 6 is slightly less than twice the diameter of one bottle, so that the bottles contained in the compartment are piled in two columns and are relatively offset in such a way that only one bottle in each compartment, i.e. the one nearest the outlet opening, needs to be supported to insure that none of the other bottles in either column can drop down and leave the compartment.

The bottom of each compartment is provided (FIG. 2) with a slidable transverse arm 10 on which the lowermost bottle rests, the axis of the arm being parallel to the axes of the bottles and lying normally in the vertical axial plane of the lowermost bottle. The arm 10 is reciprocable, in a direction transverse to its axis, from right to left and from left to right while remaining parallel to the axes of the bottles so that its own axis alternately becomes co-planar with the axes of the bottles of each of the two columns. The arm 10 is provided upon its opposite extremities with a ball-bearing-supported caster 13 and a sleeve 14 which are respectively displaceable along the beam 11 and a horizontal rod 12 parallel thereto.

The caster 13 rides upon the beam 11 while the sleeve 14 engages the guide rod 12 to keep the arm 10, which is rigidly secured to sleeve 14, perfectly aligned during the lateral movement.

An extension 15 of the arm 10 is connected to the rod of a piston 16 slidably received in a double-acting cylinder 17. The piston 16 is displaceable in a direction perpendicular to the axis of arm 10 and thus reciprocates the latter.

Each hydraulic cylinder 17, associated with a respective compartment 2, 3, 4, 5, 6, is connected by means of a pair of pipes 22, 23 to the central distributor 8 (FIGS. 2 to 6) through respective solenoid valves generally designated 25 in FIGS. 3 and 6 but shown separately at 25², 25³, 25⁴, 25⁵, 25⁶ in FIG. 4. The distributor 8 comprises

a flat-bottomed annular chamber 27 on which there are radially disposed, symmetrically about the channelled stem 8' of the distributor, the five radially displaceable slide valves 25² etc. controlled by respective solenoids generally designated 26 (but shown in FIG. 4 at 26², 26³, 26⁴, 26⁵, 26⁶) and by restoring springs 30. These springs are adapted to return the corresponding slide valves to their initial position of closure near the center of the chamber 27.

On the flat bottom 27a of the distributor chamber 27, under each slide valve 25, there is a set of three aligned ports 31, 32, 33, the two outer ports 31 and 33 being in communication with the two pipes 22, 23 of the corresponding hydraulic cylinder 17 while the central port 32 is in communication, via a compartment 27b of distributor 8 and a bore 8" of its stem 8', with the discharge pipe 34 which is connected with the reservoir 35 (FIGS. 1 and 6). The high-pressure pipe 36 establishes communication between the delivery side of the safety-valve-equipped pump 36' (the conventional safety valve is indicated schematically at 153 in FIG. 7) and a channel 8" of stem 8' leading to the chamber 27 of the distributor 8, while the low-pressure pipe 37 extends from the intake side of the pump 36' to reservoir 35.

The front of the automatic vending machine is provided with a conventional slot guide (not shown) for the introduction and passage of a coin or token. The coin or token, during its passage in the slot, momentarily operates a switch 40 (FIG. 7) which energizes a master relay 41. The vending machine is provided with several control and selector elements such as push-buttons indicated, in the electrical circuit of FIG. 7, at 43 and 43', each of these selector members being individual to a group of compartments as hereinafter described.

FIG. 6 is a schematic view of the hydraulic circuit showing, for a better understanding of the operation, only one cylinder 17 with its solenoid 26 energized and with the corresponding slide valve 25 displaced outwardly toward the periphery of the distributor chamber 27. The oil under pressure delivered by the pump 36' via pipe 36 flows from chamber 27 through the uncovered inner port 31 and left-hand pipe 22 to shift the piston 16 of cylinder 17 from left to right (as viewed in FIG. 2), while fluid on the opposite side of the piston is discharged through the right-hand pipe 23, outer port 33, slide valve 25, central port 32 and pipe 34 into the reservoir 35. When the solenoid 26 is de-energized the slide valve 25, owing to the action of the spring 30 (FIG. 3), returns to its initial position near the center of the chamber 27 and establishes communication between the left-hand pipe 22 and the discharge pipe 34. The piston 16 is now in position to be shifted from right to left (FIG. 2) if in a succeeding cycle the central chamber 27 is provided with a fresh stream of oil under pressure and if, concurrently, the solenoid 26 has not been excited. If in the succeeding cycle fresh oil under pressure is delivered to the chamber 27 and if, at the same time, the solenoid 26 is energized, the piston will not be displaced because the pressure will tend to push it further in the previous direction, that is, from left to right.

The electrical circuit of FIG. 7 includes the main switch 40 operated by the coin and the master relay 41 which is energized when the main switch 40 is closed and allows current to flow through the wires 44, 45 to the cascade-connected push-buttons 43 and 43'. Switch 40 and the winding of relay 41 are connected in series across bus bars 46, 47 respectively connected to the main conductors L₁ and L₂.

Each push-button 43 and 43' is included in the circuit of a respective control relay 48 or 48' which is provided with a plurality of armatures 49, 50, 51 or 49', 50', 51', the armatures 50 and 50' being designed to close an associated pair of switching contacts 52 or 52' if open and to open them if closed when the corresponding relay is operated by the closure of the respective push-

button 43 or 43'. This actuation of contacts 52 and 52' may be brought about by any suitable mechanical coupling thereof with the armatures 50 and 50', e.g. by a cam stepped via a conventional pawl-and-ratchet drive.

Closure of the switching contacts 52, for example, causes the energization of the solenoid 26 of the slide valve corresponding to the depressed pushbutton. The reversal of armature 49 simultaneously starts the motor 136 of pump 36' whose pressure-responsive safety cut-out 153 is serially connected in a holding circuit for motor 136. The latter is of a type having a common lead connected to one side of the power line so that it operates when energized via either of two leads by the respective switch means associated therewith, these switch means being connected to the other side of the power line.

When a coin is inserted into the slot of the machine, the operation of the switch 40 energizes the relay 41 which locks over the back contacts of armatures 51, 51' and supplies current to the pushbuttons 43, 43'. The momentary depressing of the pushbutton 43, for example, energizes the relay 48, opens the holding circuit of relay 41 at armature 51 and cuts off the current to the other pushbutton 43'; armature 49 is reversed to start the motor 136 which is maintained operated, independently of pushbutton 43, through valve contacts 153 as long as the relay 48 continues energized. The depressing of the pushbutton 43 also attracts armature 50 onto its front contact to supply current to the contacts 52 and 52'. Only the contacts 52, corresponding to the depressed pushbutton 43, are reversed whereas contacts 52' remain in the closed or open position they had occupied in the last cycle.

Though it will be apparent that the system of FIG. 7 may readily be extended to cascade as many pushbuttons 43, 43' etc. and control relays 48, 48' etc. as there are compartments for the storage of articles in the machine, there has been shown in the drawing a simplified arrangement in which the five solenoids 26² to 26⁶, respectively associated with the compartments 2 to 6, are controlled from just the two relays 48 and 48'. Contacts 52 of relay 48 are connected in series with the parallel-connected windings of three solenoids 26², 26³, 26⁴ for compartments 2, 3 and 4 which, it will be assumed, all contain bottles with the same kind of drink; similarly, contacts 52' of relay 48' are connected to the windings of the two remaining solenoids 26⁵, 26⁶ which control the dispensing of another type of beverage from the compartments 5 and 6. The connection from the solenoid windings to bus bar 47 (contacts 52 and 52' being connectable to bus bar 46 via the associated armatures 50 and 50') serially includes respective circuit breakers 154², 154³, 154⁴, 154⁵, 154⁶ which are normally held closed by the lowermost bottle in the associated storage compartment. The first three of these circuit breakers, which together with the corresponding solenoids form a selector unit 126, are connected in a lockout circuit so that, beginning with solenoid 26², the three solenoids of that unit will be successively switched into the load circuit of relay 48 as the compartments 2 and 3 become exhausted; when the last bottle is drawn from compartment 4, circuit breaker 154⁴ reverses in series with breakers 154², 154³ to cut out the last of these solenoids and to energize an indicator lamp 152 in an obvious circuit. In like manner the solenoids 26⁵, 26⁶ of the other selector unit 126' operate in consecutive sequences under the control of associated circuit breakers 154⁵ and 154⁶, an indicator lamp 152, being lit by these breakers when both compartments 5 and 6 are empty. A switch 254, ganged with circuit breaker 154⁴, energizes via breaker contacts 154⁵ and 154⁶ an electromagnet 250 which may serve, for example, to block further operation of the machine by obstructing its coin slot.

It will be noted that the pairs of switching contacts 52, 52' are interconnected by a lead 521 so that actuation of

say, the relay 48 will result in the energization of one of the solenoids 26², 26³, 26⁴ and/or one of the solenoids 26⁵, 26⁶ if contacts 52, previously open, are closed by the operation of that relay and/or if contacts 52' are closed, their position being unaffected by the actuation of relay 48. This insures that any previously energized solenoid associated with the unoperated relay, here relay 48', is promptly re-energized to return its valve 25 to the position it occupied in the preceding cycle, against the force of their restoring springs 30 which in the open-circuit condition of the system always maintain all the solenoids in their normal positions illustrated in FIG. 3, so that the associated pistons 16 will not be shifted. Thus, since only the contacts 52 reverse upon the operation of relay 48, only a solenoid of unit 126 will be rendered effective (i.e. switched from energized to de-energized condition or vice versa) to reverse the pressure acting upon its piston 16 and to shift the associated slider 10 (FIG. 2) in one sense or the other to release a bottle from either column of its compartment. When the piston 16 has reached the end of its stroke, pressure builds up in pump 36' until the contacts of cutout 153 open to stop the motor 136. The system then returns to its quiescent state.

I claim:

1. In a vending machine having a plurality of compartments for the storage, in two interleaved vertical columns, of articles to be individually dispensed, in combination, a reciprocable element at each of said compartments adapted by its displacement to discharge a single article therefrom, a plurality of hydraulic cylinders, a plurality of double-acting pistons respectively received in said cylinders and linked each with one of said elements, a pair of conduits for each of said cylinders respectively connected thereto at opposite ends, a source of fluid under pressure, a plurality of valves each having two operating positions for admitting fluid from said source to either conduit of a respective pair, reversible control means for each of said valves adapted to displace the same between said operating positions, and energizing means for said control means selectively operable for alternately displacing each of said valves in opposite directions between said operating positions, thereby correspondingly reciprocating the respective pistons, and displacing a respective element from engagement with the lowermost article in the respective compartment arrayed in one of said columns thereof into engagement with the lowermost article of the other column.

2. In a vending machine having a plurality of compartments for the storage of articles to be individually dispensed, in combination, a reciprocable element at each of said compartments adapted by its displacement to discharge a single article therefrom, a plurality of hydraulic cylinders, a plurality of double-acting pistons respectively received in said cylinders and linked each with one of said elements, a pair of conduits for each of said cylinders respectively connected thereto at opposite ends, a reservoir for hydraulic fluid, distributor means for said fluid having said pairs of conduits connected thereto, pump means for said fluid, a hydraulic circuit interconnecting said reservoir, said pump means and said distributor means, said distributor means comprising a plurality of independent valves each associated with a respective pair of said conduits and selectively operable for reversibly admitting fluid under pressure from said pump means and returning fluid to said reservoir by way of the associated pair of conduits whereby the piston in the cylinder connected to said associated pair is shifted in either of two directions upon a displacement of the corresponding valve into a first and into a second position respectively, and electric control means for alternately displacing a selected valve between said positions in successive operating cycles, each of said compartments being adapted to store said articles in two interleaved vertical columns, said reciprocable element of each compartment being positioned at the bottom thereof for releasably

supporting the momentarily lower one of the lowermost articles of said columns whereby the article so supported is discharged from the respective compartment and all other articles therein drop down one step upon each unilateral displacement of said element.

3. The combination according to claim 2, further comprising coin-actuated switch means and circuit means connected to said switch means and to said control means for operating the latter for one cycle upon each actuation of said switch means.

4. The combination according to claim 3 wherein said control means comprises a plurality of relays and a plurality of selector members connected in a preference circuit for operating a selected single one of said relays upon each actuation of said switch means in an off-normal position of a corresponding selector member.

5. The combination according to claim 4 wherein each of said relays is provided with a pair of switching contacts adapted to be alternately closed and opened in successive operations of the relay, said control means further including an individual actuator for each of said valves with an energizing circuit including the pair of switching contacts of one of said relays.

6. The combination according to claim 5 wherein said actuator comprises a solenoid energizable over said switching contacts for displacing the associated valve into its first position, and spring means for restoring the valve to its second position upon de-energization of said solenoid, each of said relays including normally open contacts connected in parallel with the normally open contacts of the other relays and to all pairs of switching contacts for completing the energizing circuit of all actuators with closed switching contacts upon the operation of any of said relays.

7. The combination according to claim 5 wherein a plurality of said actuators are provided with a common energizing circuit including a single pair of said contacts, and switchover means in said common circuit controlled by the articles in one of said compartments for preferentially operating the associated actuator until the articles therein are exhausted and for thereupon rendering effective another actuator sharing said common circuit.

8. In a vending machine having a plurality of compartments for the storage of articles to be individually dispensed, in combination, a reciprocable element at each of said compartments adapted by its displacement to discharge a single article therefrom, a plurality of hydraulic cylinders, a plurality of pistons respectively received in said cylinders and linked each with one of said elements, a pair of conduits for each of said cylinders respectively connected thereto at opposite ends, a reservoir for hydraulic fluid, distributor means for said fluid having said pairs of conduits connected thereto, pump means for said fluid, a hydraulic circuit interconnecting said reservoir, said pump means and said distributor means, said distributor means comprising a plurality of independent valves each associated with a respective pair of said conduits and selectively operable for reversibly admitting fluid under pressure from said pump means and returning fluid to said reservoir by way of the associated pair of conduits whereby the piston in the cylinder connected to said associated pair is shifted in either of two directions upon a displacement of the corresponding valve into a first and into a second position respectively, and electric control means for alternately displacing a selected valve between said positions in successive operating cycles, said pump means being provided with a motor and with a pressure-responsive switch connected to de-energize said motor upon attainment of a predetermined fluid pressure following displacement of each piston to a terminal position, said motor having an operating circuit including said pressure-responsive switch and adapted to be closed by said control means at the beginning of each cycle.

9. The combination according to claim 2 wherein said

reciprocable element is an arm rigidly connected at one end with the associated piston and provided with parallel guide rails maintaining it parallel to itself during reciprocation.

10. In a vending machine having a plurality of compartments each provided with guide means for receiving two columns of articles in staggered relationship, in combination, a reciprocable element positioned at the bottom of each compartment and adapted by its displacement to discharge a single article therefrom, a plurality of hydraulic cylinders each respectively assigned to one of said compartments, a plurality of double-acting pistons respectively received in said cylinders and linked each with one of said elements, a source of fluid under pressure, transmission means connecting said source with said cylinders, central hydraulic control means in said transmission means for directing the flow of fluid from said source selectively to said cylinders, and selector means for operating said central hydraulic control means to displace selected ones of said pistons, thereby individually releasing articles from the compartments associated with said selected ones of said pistons.

11. In a vending machine having a plurality of compartments each provided with guide means for receiving two columns of articles in staggered relationship, in combination, a reciprocable element positioned at the bottom of each compartment and adapted by its displacement to discharge a single article therefrom, a plurality of hydraulic cylinders each respectively assigned to one of said compartments, a plurality of double-acting pistons respectively received in said cylinders and linked with respective elements, a source of fluid under pressure, a pair of conduits for each of said cylinders respectively connected thereto at opposite ends, a central multiple distributing valve adapted to distribute the fluid from said source to a respective one of said cylinders via one of said conduits of a respective pair, and selector means for operating said distributing valve to displace a selected one of said pistons, thereby individually releasing articles from the compartment associated with said selected one of said pistons.
